[57] CLAIM

The ornamental design for a compact disk shelf case sidewall member, as shown and described.

DESCRIPTION

FIG. 1 is a partial top perspective view of a compact disk shelf case incorporating a compact disk shelf case sidewall member embodying my new design;

FIG. 2 is a front elevational view of the compact disk shelf case sidewall of FIG. 1 incorporating the compact disk shelf case member on its top and bottom ends;

FIG. 3 is a side view thereof; and,

FIG. 4 is a top plan view thereof.

The dotted lines are for illustration only and do not constitute part of the claimed design.
